Primary Examiner — Michelle E. Wilson
Assistant Examiner — Sanjeev Paul

(57) **CLAIM**

The ornamental design for a multi-functional spectacle temples, as shown and described.

DESCRIPTION

FIG. 1 is a left, front perspective view of a multi-functional spectacle temples showing my new design;

FIG. 2 is a right, front perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another left, front perspective view thereof showing the temple in different angle.

1 Claim, 8 Drawing Sheets
